UNITED STATES PATENT OFFICE.

WILLIAM F. REGAN, OF NEW YORK, N. Y., ASSIGNOR TO UNIVERSAL PAPER BOTTLE CO., OF WILMINGTON, DELAWARE, A CORPORATION OF DELAWARE.

COLLAPSIBLE MANDREL.

1,186,498.

Specification of Letters Patent. Patented June 6, 1916.

Application filed February 23, 1912, Serial No. 679,263. Renewed September 1, 1915. Serial No. 48,572.

To all whom it may concern:

Be it known that I, WILLIAM F. REGAN, a citizen of the United States, residing in the city of New York, borough of Brooklyn, 5 county of Kings, and State of New York, have invented a certain new and useful Improvement in Collapsible Mandrels, of which the following is a specification.

This invention pertains to a collapsible 10 mandrel, and the object of the invention is to permit of a paper receptacle having a crimped neck, such as a paper milk bottle, to be formed thereon while the mandrel occupies an expanded position, whereupon 15 said mandrel is collapsed and withdrawn from the bottle. In the mechanism heretofore employed for this purpose, the crimping devices were of such character that the crimps were produced by folding the paper 20 material between the members composing the mandrel. These devices, however, failed to operate successfully because of the fact that the paper material was frequently torn during collapsing of the mandrel.

25 The present invention overcomes the defects referred to, and others, in prior mechanisms, and embodies a collapsible crimping mechanism wherein the folds or crimps in the paper material are produced by folding 30 said paper material within the members in contradistinction to between the members.

More specifically stated, the invention embodies a plurality of collapsible crimping 35 members, which form a mandrel, each of said crimping members being provided with a groove or channel, and coöoperating crimping fingers positioned in alinement with the said grooves or channels and operable to 40 press the paper material therein, thereby producing the crimps or folds.

Other features of the invention, and the advantages thereof, will appear in the course of the following detailed description 45 taken in connection with the drawings.

In the accompanying drawings, there is illustrated one practical embodiment of the invention, but the construction shown therein is to be understood as illustrative, only, 50 and not as defining the limits of the invention.

Figure 1 is a side elevation of the improved mandrel illustrating the same in an expanded condition. Figs. 2 and 3 are ver-

tical cross sections on the lines 1—1 and 55 2—2, respectively, of Fig. 1. Fig. 4 is a longitudinal section through the mandrel when expanded. Fig. 5 is a longitudinal section through the mandrel in a collapsed condition. Fig. 6 is a sectional view through 60 the mandrel in an expanded operative condition, and showing certain crimping fingers in coöperative relation to the grooves or channels in the members composing the mandrel. Fig. 7 is a cross section, on the 65 line 6—6 of Fig. 6, illustrating the position of the crimping fingers in alinement radially with the channels or grooves in the members of the mandrel.

Mandrel shaft 10 is reduced for a part of 70 its length, as at 11, thereby producing an annular shoulder 12 intermediate the mandrel and the reduced part thereof. Two collars 13, 14 are attached rigidly to the mandrel shaft for rotation therewith, and 75 between these collars is positioned a spacing thimble 15, the respective end portions of which are in engagement with the collars so as to retain the latter in predetermined 80 positions upon the reduced part 11 of the mandrel shaft. Collar 13 is fitted on the mandrel shaft for engagement with the annular shoulder 12 thereon, and this collar is provided with a binding screw 16 adapted for engagement frictionally with the reduced 85 part of the mandrel shaft, whereby the collar is clamped on said part 11 so as to be in contact normally with the shoulder 12. Collar 14 is fitted on the extremity of part 11 of the mandrel shaft, and it is provided with a binding screw 17, whereby said collar 14 is retained fixedly in position on the part 11 and in contact with spacing 90 thimble 15. Collar 13 is provided with a series of longitudinal grooves 18, and a 95 similar series of grooves 19 is provided in collar 14, the purpose of the grooves 18, 19 being to accommodate the end portions of certain links, whereby said links may be folded into compact relation to the mandrel 100 shaft, as will hereinafter appear.

Loosely mounted on the mandrel shaft is a head, preferably collapsible, through which the shaft is free to slide in certain parts of its operation, said head serving to 105 pivotally support one end of certain members composing the collapsible and expandible mandrel. Various forms of heads may

be employed, but as shown in Figs. 4, 5 and 6 of the drawings, the head is preferably collapsible and embodies a sleeve 20, a collar 21, and a divided ring having sections 22. 5 The sleeve 20 is provided at one end with a flange 23, the other end of said sleeve having a male thread on which is screwed a nut 24. The collar fits snugly on the sleeve between flange 23 and nut 24 so that the collar is 10 clamped fixedly in position relative to the sleeve. Said collar is provided at one end with an annular flange 25, and in the other end portion of said collar is a series of notches or grooves 26 adapted to receive the 15 end portions of one series of mandrel members. Collar 21 is provided, also, with a series of notches 27 intermediate its ends, and around this notched portion of the collar is fitted the sections composing ring 22, 20 each section of the ring being provided with a lug 28, through which passes a pin 29, for the purpose of pivotally connecting the ring section to collar 21 of the head. The sections of the ring extend beyond that edge of 25 the collar having notch 26, said extended ends of the ring section being formed with an inclined flange 30 positioned for engagement with the expansible mandrel members. The pivoted sections 22 of the ring are 30 pressed in one direction by springs 31, each spring being screwed to flange 25 of the collar, and the free end of said spring being bent so as to engage with the inner face of one section composing the expansible 35 ring 22.

The mandrel embodies in its construction two series of members 32, 33, said members extending generally in a direction lengthwise of the mandrel and being foldable into 40 compact relation thereto, as shown in Fig. 5, or movable to operative positions away from the mandrel shaft, as shown in Figs. 1, 4 and 6.

Members 32 are in the form of straight 45 bars, one end of each bar being positioned within a recess 26 of collar 21 and said end of the bar being pivoted by a pin 34 to collar 21 of the head. The bars 33 of the other series are positioned in alinement with bars 50 32 of the first-named series, and the alined bars of the two series 32, 33 are shown as being pivoted directly together by pins 35.

It will be seen that the bars 32 composing one series of members are pivoted directly 55 to the head so as to be pivotally supported for movement relative to the mandrel shaft, but at their other ends, these members 32 are supported by links 36 which connect said members operatively with collar 13 fixed on 60 the mandrel shaft. Each link 36 is positioned at one end within a recess 18 of collar 13, on which said end of the link is pivotally connected by a pin 37. The outer end of said link 36 is fitted in a slot 38 provided 65 in member 32 in advance of the pivotal con-

nection 35 between members 32, 33, the outer end of said link being pivotally attached to one member 32 by pin 39.

Members 33 are pivotally supported at one end by the pins 35 which connect said 70 ends with members 32, but the other ends of members 33 are supported by links 40. Each link 40 is fitted in a recess 19 of collar 14 to which the link is pivoted by a pin 41, whereas the other end of each link 40 is fitted in 75 a slot 42 provided in the rear portion of member 33, to which member said end of the link is connected by means of a pin 43.

A salient feature of the invention consists 80 of grooves or channels 44 extending longitudinally of members 32, each member 32 having one of said grooves or channels 44 provided in the material composing the bar forming said member. The channel or groove 44 in each member opens radially 85 through the outer face of the member, as clearly shown in Figs. 2 and 3, and, preferably, each groove tapers in the direction of its length, the deepest part of the groove being adjacent to the pivotal connection 90 of the member to the head, whereas the shallow part of the groove is next to slot 38 in which is positioned one of the links 36. It is preferred to provide each member 33 with a longitudinal groove 45, the same being preferably uniform in depth. The members 32, 33 being pivotally connected at their adjacent ends by pins 35, the grooves 44, 45 in said members are in alinement with each other and extend for practically the length 95 100 of the mandrel.

When the mandrel is expanded, members 33 are retained in parallel relation to mandrel shaft 10, whereas members 32 are inclined relative to said mandrel shaft, whereby the paper material may be formed upon the mandrel so as to produce a bottle or similar container having a tapering neck portion. Upon collapsing the mandrel, members 32 and 33 fold into compact relation 110 parallel to the mandrel, as shown in Fig. 5, whereby the external diameter of the mandrel is reduced sufficiently for the members to be withdrawn from the bottle through the neck thereof at the tapering 115 portion of said bottle. It is preferred to expand and contract members 32, 33 by moving the mandrel in the direction of its length so that it will have a sliding movement through the head. With the mandrel in an 120 expanded position, as shown in Figs. 1, 4 and 6, the paper material may be folded or wrapped one or more times around members 33, after which that part of the paper material which envelops members 32 is pressed 125 or folded inwardly by the action of crimping fingers, as a result of which operation of the crimping fingers, the paper material will be folded into the longitudinal channels 44 of members 32, thus resulting in plaited or 130

5 folds which impart the desired taper to the neck of the bottle or other container. The crimping fingers 46 are pivoted at 47 to sliding head 48, said fingers being actuated by springs 49, but this crimping mechanism forms no part of the present invention, for the reason that it constitutes the subject matter of a separate application filed by me, January 8, 1912, Serial No. 669,945. The 10 crimping fingers 46 are carried by a head which has sliding movement relative to the mandrel as well as rotative movement simultaneously with the mandrel in the operation of producing a paper bottle, all as will more 15 fully appear by reference to the aforesaid application, but when the crimping fingers and their operating mechanism are employed in conjunction with the improved mandrel, it is essential that the crimping 20 fingers 46 be positioned opposite to, or in alinement radially with, grooves or channels 44 in members 32 of the collapsible mandrel, whereby upon the inward movement of said crimping fingers 46 toward the 25 mandrel, the paper material will be pressed and folded into grooves or channels 44 of said members 32, in contradistinction to the operation of prior mandrels wherein the paper material is folded into plaits between 30 the members composing said mandrel, as a result of which operation, the improved mandrel acts efficiently in producing the folds or plaits in the paper material in such manner that the paper, when the mandrel 35 is collapsed, will not become torn and mutilate the container.

The operation of the mandrel is as follows:—With the mandrel in the expanded position shown in Figs. 1 and 4, the paper 40 material is fed to the mandrel so as to envelop members 32, 33, and said mandrel is rotated for the purpose of coiling or winding the paper around, and in contact with, members 33, after which the rotation of the 45 mandrel is stopped. Head 48 carrying crimping fingers 46 now slides into position over the mandrel, and the paper wound thereon, for the purpose of bringing crimping fingers 46 into position over that part 50 of the cylindrical paper roll which envelops members 32, whereupon the crimping fingers are operated by pressing them inwardly, as a result of which the paper is contracted around members 32, and some of the paper 55 material is pressed by the fingers 46 into tapering channels 44, thereby producing tapering folds or plaits in the paper material and giving the desired taper to the neck of the bottle or similar container. Some of 60 the paper material extends beyond the members 32 and overlaps the divided ring 22, of the collapsible head, thus resulting in the formation of a mouth flange beyond the tapering neck of the container. While the 65 fingers 46 are pressed into the folds or

plaits of the paper composing the container, the mandrel is collapsed by moving the mandrel shaft 10 relative to the head, such endwise movement of the mandrel drawing collars 13, 14 toward the right and pulling 70 on the links 36, 40 so as to fold said links and members 32, 33 into parallel relation to the mandrel shaft, as shown in Fig. 5. The mandrel in a collapsed condition may now be withdrawn from the bottle or container 75 through the contracted neck and mouth portions thereof, the plaits or folds in the neck portion of the container sliding through the grooves or channels 44, 45 of members 32, 33, respectively. At the proper time, the crimping fingers 46 are released and the head 48 with said fingers 46 are withdrawn from the paper bottle or other container by imparting the endwise movement to said head 48. The resulting paper bottle may be discharged from the machine in any suitable 80 way, and at a proper time in the operation of forming said bottle, a closure or bottom is positioned within the open end of the cylindrical part of the bottle, the bottom and 85 the body of the bottle being united in any desired way. After the bottle shall have been formed and discharged the mandrel is moved back to an operative position, mandrel shaft 10 operating to move the collars 13, 14 90 away from the head, and thereby expand links 36, 40, whereupon members 33 are pressed outwardly into positions parallel to the mandrel shaft, and members 32 are moved into positions inclined to the mandrel shaft, 95 as well as inclining said members 32 to members 33 and the head. The paper may now 100 be again fed to the mandrel and the operations of feeding, winding, and crimping the paper repeated.

In addition to performing the function of a support for members 32, the head with the collapsible ring 22 serves as a means for forming the mouth flange of the container or bottle. The paper which is to be wrapped or coiled around the mandrel should be of such length as to extend from the free ends of members 33 to and over the collapsible ring 22, and after the paper shall have been coiled to produce the cylindrical roll as described, and said paper shall have been crimped to produce the folds or plaits of the tapering neck, an edge portion of the paper roll is collapsed around the ring 22. Said ring is provided with a shoulder 22^a against 110 which the edge of the paper is adapted to about, and subsequent to the operation of crimping the paper, the neck portion of the paper bottle is reinforced by winding a strip of paper around the mouth flange of the container. This strip of paper is coiled several times around the mouth portion of the bottle so as to confine the crimps or folds in proper relation to the body of the bottle, said mouth flange strip being wound 115 120 125 130

tightly around the paper material. For the purpose of easy removal of the ring 22 from the container, said ring is made collapsible, and when the mandrel is collapsed to release members 32, 33 from frictional contact with the paper material, ring 22 is also collapsed in order to allow the easy withdrawal of the mandrel from the paper bottle.

Although it has been stated that the paper is wound one or more times around the mandrel, it is preferred in one embodiment of the invention to preliminarily roll the paper into a cylindrical roll independently of the mandrel, to move or position said mandrel within the cylindrical roll subsequent to the production of said roll, thereafter expand the mandrel so that members 33 will support the cylindrical roll, then crimp or fold the paper material by the operation of crimpers which press a part of said material into the grooves of members 32, and then proceed as heretofore described in completing the formation of the bottle or other container. The mechanism for performing these operations will constitute the subject matter of a separate application, but in this application it is desired to secure protection for the new form of construction composing the collapsible and expandible mandrel.

Having thus fully described the invention, what I claim as new, and desire to secure by Letters Patent is:—

1. In a mandrel, the combination of a plurality of separate bars composed of substantially rigid material, each bar having in the outer face thereof a longitudinal channel, and a plurality of coöperating members operable to press paper into said channels, whereby crimps are produced in said paper.

2. In a mandrel, the combination of a plurality of collapsible channeled members, a plurality of coöperating members operable to press paper into said channels, whereby crimps are produced in said paper, and a plurality of other collapsible members coöperating with said channeled members.

3. In a mandrel, the combination of a plurality of inclined collapsible channeled members, a plurality of coöperating members operable to press paper into said channels, whereby crimps are produced in said paper, and a plurality of substantially parallel collapsible members coöperating with said channeled members.

4. In a collapsible mandrel, a mandrel shaft, a series of members normally parallel to said mandrel shaft, a second series of members provided with channels or grooves, and means connecting the members of the

first and second series with said mandrel shaft for expanding the mandrel in such manner that the first series of members are substantially parallel to the mandrel shaft whereas the second series of members are inclined relative to the mandrel shaft.

5. In a collapsible mandrel, a mandrel shaft, a series of members each provided with a groove which tapers lengthwise of the member, means connecting said members with the mandrel shaft, a second series of members, and means connecting the members of the second series with said mandrel shaft.

6. In a collapsible mandrel, a mandrel shaft, a series of members each provided with a longitudinal groove or channel, a second series of members each having a longitudinal groove or channel, and separate connecting means for attaching the members to the mandrel shaft for expanding and contracting the members relative to said shaft.

7. In a collapsible mandrel, a mandrel shaft, a series of members each provided with a groove or channel which tapers lengthwise of the member, a second series of members each having a groove or channel which is substantially uniform in depth, and means for connecting the members of the first and second series with the mandrel shaft to secure an expanding or contracting movement of said members relative to said shaft.

8. In a collapsible mandrel, a mandrel shaft, a head loose thereon, a series of channeled members each pivoted at one end to said head, a series of links each connecting the other end of one member with the mandrel shaft, a second series of members, and links connecting said members of the second series with the mandrel shaft, said members of the first series being movable to inclined positions, and the members of the second series being movable to parallel positions relative to the mandrel shaft when the mandrel is expanded.

9. In a collapsible mandrel, a mandrel shaft, a head loose thereon, a series of channeled members each pivoted at one end to said head, a series of links each connecting the other end of one member with the mandrel shaft, a second series of channeled members each pivoted at one end to an adjacent member of the first series, and other links connecting the opposite end portions of the members of the second series with the mandrel shaft, all of said members being foldable, when the mandrel is collapsed, into compact parallel relation to the mandrel shaft, whereas upon expansion of the mandrel, the first series of members are movable to inclined positions and the second series of members retain their parallel relation to the mandrel shaft.

10. In a collapsible mandrel, a head embodying a sleeve, a collar fixed thereto, and a divided ring composed of spring-pressed sections pivoted to said collar, combined with a mandrel shaft passing loosely through the sleeve, a series of members piv-

oted to the collar, and links connecting the members to the mandrel shaft, said sections of the divided ring having frictional contact with the pivoted members rearwardly of the pivotal connection between the members and the collar.

11. In a collapsible mandrel, a mandrel shaft, a rotatable head having a collapsible ring upon which an edge portion of the paper is adapted to be wound, and members operatively connected with the mandrel shaft, said members and the ring being collapsible relative to the mandrel shaft for the purpose of easily withdrawing the mandrel from a container.

12. In a collapsible mandrel, a mandrel shaft, a rotatable head embodying a sec-

tional ring the sections of which are spring-actuated, and members connected with said mandrel shaft and with said rotatable head, 20 said members and the sectional ring being collapsible relative to the mandrel shaft, whereby the entire mandrel and the head thereof are adapted to be released from frictional engagement with the container and to 25 be withdrawn easily therefrom.

In testimony whereof I have signed my name to this specification in the presence of two subscribing witnesses.

WILLIAM F. REGAN.
